UNITED STATES PATENT OFFICE

CHARLES H. LYNE, OF MIAMI, FLORIDA

SURFACING MACHINE

Application filed September 4, 1928. Serial No. 303,904.

My invention relates to metal surfacing machines, and more particularly to a portable manhole casing interior surfacing or finishing machine.

5 An object of the invention is to provide a machine of this character having a revoluble surfacing element which is advanced longitudinally over the work so that the entire surface being operated on will be evenly 10 surfaces.

15 The invention further provides a portable machine which is rotatably supported on the work and incident to its rotation about the same automatically feeds a cutting or surfacing element step by step.

20 With the preceding and other objects and advantages in mind, the invention consists in the novel combination of elements, construction and arrangement of parts to be hereinafter specifically referred to, claimed 25 and illustrated in the accompanying drawings, wherein:—

Figure 1 is a top plan view of the invention in operative position on a manhole casting and having parts broken away,

Figure 2 is a horizontal section taken on line 2—2 of Fig. 1, and

Figure 3 is a fragmentary vertical section on line 3—3 of Fig. 2.

30 Referring to the invention in detail, a circular trackway 5 to be received on the upper edge of a manhole casing 6 and retained thereon by radially disposed set screws 7 is provided.

35 Removably and rotatably mounted on the trackway 5 is a metallic casting 10 having a plurality of radially disposed arms 11 which extend close to the inner edge of the trackway. Each of the arms is formed with an upstanding extension 12 at its outer end, provided with angularly disposed transverse openings 13 through which angularly disposed handles 14 pass, for the purpose of 40 rotating the casting. A horizontal shaft 15 passes transversely through each of the extensions adjacent its lower end and carries a flanged roller 16 which is received on the trackway.

45 For the purpose of clamping the casting against vertical displacement, a horizontal

clamping bar 17 of a length to be snugly received within the manhole casing and having upstanding lugs 18 at its ends to contact with the under face of the usual annular seat in the manhole casing is provided. Set screws 55 19 pass through these lugs for binding engagement with the interior of the manhole casing. A vertical shaft 20 rises from the upper face of the clamping bar centrally of the ends of the latter and passes through a hub 21 formed at the center of the casting. Anti-friction elements 22 are arranged in the hub to eliminate friction. The upper end of the shaft projects beyond the hub and retaining nuts 24 to hold the casting and clamping bar in assembled relation.

50 The under face of one of the arms 11 is formed with a longitudinally extending rectangular sleeve 25 in which a longitudinally movable rectangular body 26 is slidably mounted, the latter at its outer end having an angularly disposed transverse opening 27 through which a surfacing element or blade 28 passes. The blade 28 is maintained in proper adjustment to the upper face of the manhole casing seat by a set screw 29 passing transversely through one end of the body 26. The body 26 is limited in its longitudinal movement by a stop 30 projecting from the upper wall of the sleeve 25 and into a longitudinal recess 31 in the upper face of the body. By reason of the end walls of the recess 31 contacting with the stop 30 the body 26 is limited in its longitudinal movement.

55 In order to advance the body 26 step by step over the work so as to contact with a new area each revolution of the casting, a vertically disposed star wheel 32 is mounted on the arm 11 equipped with the sleeve 25 60 and projects through a transverse opening 33 in such arm, rearwardly of the sleeve. The star wheel is provided with a lateral trunnion 34 at one side which is supported in a lateral bearing 35 formed on the hub in 65 opposed relation to the sleeve 25. An internally threaded sleeve 36 projects from the opposite face of the star wheel and into the sleeve 25 where it threadedly engages a horizontally disposed threaded stem 37 rigid with 70

the inner end of the body 26. Retained on the shaft 20 below the casting by a set screw 38 engaged with the shaft 20 is a collar 39 provided with a laterally projecting pin 40 lying in the path of the star wheel.

5 In practice, the casting is rotated on the circular trackway by successively pushing the handles 14 from the operator. As the casting is rotated the blade 28 describing a 10 circle, removes the burr or roughness from the work in its path. By reason of the lateral fingers or segments of the star wheel successively engaging the pin 40, the threaded 15 stem 37 will be moved outwardly step by step to dispose the blade on a new surface 20 of the work. Due to the fact that the blade successively contacts with a new area of the work, the entire surface being operated upon will be evenly finished or surfaced.

20 What is claimed is:—

1. A machine for surfacing an internal lateral ledge formed on a circular body, a circular trackway to be removably positioned on the circular body, a casting within the 25 confines of the trackway, rollers carried thereby and movable over the trackway, and a surfacing element carried by the casting and movable over the ledge.

2. A machine for surfacing an internal lateral ledge formed on a circular body, a circular trackway to be removably positioned on the circular body, a casting within the 30 confines of the trackway, rollers carried thereby and movable over the trackway, and a longitudinally movable surfacing element carried by the casting and movable over the ledge.

3. A machine for surfacing an internal lateral ledge formed on a circular body, a circular trackway to be removably positioned on the circular body, a casting within the 40 confines of the trackway, rollers carried thereby and movable over the trackway, a longitudinally movable surfacing element carried by the casting and movable over the ledge, and 45 automatic means for moving the surfacing element transversely over the ledge.

4. In a machine for surfacing the internal lateral ledge provided on circular bodies, a casting revolvably mounted above the work, 50 a longitudinally movable surfacing element carried thereby, and contacting with the ledge surface, a threaded stem projecting from the surfacing element, a vertically disposed star wheel supported on the casting to one side of the surfacing element and having an internally threaded sleeve engaging the threaded stem, and a fixed pin mounted in the path of the star wheel and engageable by the latter each revolution of the casting to advance the 55 surfacing element step by step over the ledge.

5. A machine for surfacing the internal 60 annular ledges formed on circular bodies such as manhole casings, comprising a track to be removably positioned on the manhole casing, 65 a clamping bar engageable within the man-

hole casing, a shaft projecting vertically therefrom, a casting revolvable on the shaft, a plurality of radially disposed handles associated with the casing for rotating the latter, and a surfacing blade carried by the casting and movable over the ledge.

6. In a surfacing machine, a circular track to be supported on the work, a member to be anchored to the work below the track, a vertical shaft rising from the member, a casting rotatable on the track and shaft, and a surfacing element extending laterally from the casting.

7. In a surfacing machine, a circular track to be supported on the work, a member to be anchored to the work below the track, a vertical shaft rising from the member, a casting rotatable on the track and shaft, a surfacing element extending laterally from the casting, and means for successively advancing the surfacing element step by step over the work.

8. In a surfacing machine, a circular track to be positioned on the work, a casting having a plurality of horizontally disposed radially extending arms, an upstanding extension formed with each arm, rollers revolvably supported by the extension and movable over the track, and a surfacing element extending laterally from one of the arms.

9. In a surfacing machine, a circular track to be positioned on the work, a casting having a plurality of horizontally disposed radially extending arms, an upstanding extension formed with each arm, rollers revolvably supported by the extensions and movable over the track, a surfacing element extending laterally from one of the arms, and handles removably associated with the extensions.

10. In a surfacing machine, a circular track to be positioned on the work, a casting having a plurality of horizontally disposed radially extending arms, an upstanding extension formed with each arm, rollers revolvably supported by the extensions and movable over the track, a surfacing element extending laterally from one of the arms, each of the extensions having an angularly disposed transverse opening, and an angularly disposed grasping rod passing through each opening with its lower end resting on one of the arms.
